(57) **CLAIM**

The ornamental design for a footwear article, as shown and described.

DESCRIPTION

FIG. 1 is a front view of a footwear article according to the claimed design.

FIG. 2 is a rear view of the footwear article.

FIG. 3 is a right side view of the footwear article.

FIG. 4 is a left side view of the footwear article.

FIG. 5 is a top view of the footwear article; and,

FIG. 6 is a bottom view of the footwear article.

The broken lines in the figures illustrate portions of the

footwear article that form no part of the claimed design.

The inner surface portions of the footwear article shown through the openings at the rear, top, left, and right sides of the footwear article form no part of the claimed design.

1 Claim, 6 Drawing Sheets
